[57] CLAIM

The ornamental design for a putter, substantially as shown.

DESCRIPTION

FIG. 1 is a perspective view of a putter which embodies our new design, illustrating the putter from the front or putting side of the putter head;

FIG. 2 is an elevational view of the putter of the invention taken from the toe end of the putter head;

FIG. 3 is an elevational view taken from the front or putting side of the putter head;

FIG. 4 is a fragmentary elevational view taken from the rear side of the putter head;

FIG. 5 is a sectional view taken as indicated by the arrowed line 5—5 of FIG. 3, and showing the top of the putter head;

FIG. 6 is a bottom view of the putter head;

FIG. 7 is a sectional view through the putter head taken as indicated by the arrowed line 7—7 of FIG. 3; and

FIG. 8 is a fragmentary elevational view taken from the heel end of the putter head.

*FIG. 5.**FIG. 6.**FIG. 8.**FIG. 7.*
